US00D939592S

(12) **United States Design Patent** (10) **Patent No.:** **US D939,592 S**
Pfaffmann et al. (45) **Date of Patent:** ** *Dec. 28, 2021

(54) **WORK MACHINE**

(71) Applicant: **DEERE & COMPANY**, Moline, IL (US)

(72) Inventors: **Simon Pfaffmann**, Mannheim (DE); **Nicolai Tarasinski**, Frankenthal (DE); **Volker Kegel**, Mannheim (DE)

(73) Assignee: **DEERE & COMPANY**, Moline, IL (US)

(*) Notice: This patent is subject to a terminal disclaimer.

(**) Term: **15 Years**

(21) Appl. No.: **29/748,604**

(22) Filed: **Aug. 31, 2020**

(57) **CLAIM**

The ornamental design for a work machine, as shown and described.

DESCRIPTION

FIG. 1 is a top, front, left perspective view of a work machine according to our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a top, front, left perspective view of a work machine according to another embodiment of our new design;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top plan view thereof; and,

FIG. 14 is a bottom plan view thereof.

The broken line representations in the figures show unclaimed environment or boundaries, and thus form no part of the claimed design.

1 Claim, 14 Drawing Sheets
